UNITED STATES PATENT OFFICE

FREDERICK W. LODDING, OF WORCESTER, MASSACHUSETTS, ASSIGNOR TO RICE, BARTON & FALES, INCORPORATED, OF WORCESTER, MASSACHUSETTS, A CORPORATION OF MASSACHUSETTS

SLITTER

Application filed March 18, 1929. Serial No. 347,772.

This invention relates to a slitter capable of general use but particularly adapted for use on paper winding machines.

The principal objects of the invention are to provide slitting knives adapted to be rotated independently of each other at high speed, in combination with a second element for each slitting couple movable back and forth in such a way as to present a new surface to the paper at all times; to provide a second element of each slitting couple in the form of a sector shaped member; to provide means for oscillating said member about an axis so as to secure the above mentioned constantly changing surface, and to provide a construction in which the slitting segment can be swung around out of contact with the other member of the slitting couple for threading in the web.

Other objects and advantages of the invention will appear hereinafter.

Reference is to be had to the accompanying drawings in which

Fig. 1 is an end view of a winding machine provided with a preferred embodiment of this invention with parts shown in section;

Fig. 2 is a similar view in section showing the mechanism for operating the sector-shaped member;

Fig. 3 is an end view taken in the direction of the arrow 3 in Fig. 2, and

Fig. 4 is a plan taken in the direction of the arrow 4 in Fig. 2.

This invention is shown as applied to a well known type of winding machine in which the web of paper W comes in over a series of guide and tension rolls 10 to a roll 11 and from there is brought up on one of the winding rolls 12. The paper is wound up in a roll 13 resting on the two winding rolls 12 which are driven from a gear or other wheel 14 in the usual way. Between the rolls 11 and 12 the web is slit as will appear hereinafter.

From a shaft 15 of the machine by a worm drive a shaft 16 is driven which in turn in a

similar way drives a shaft 17. On the shaft 17 is a cam 18 in the groove of which is a cam roller 19 on a radial arm 20. This arm projects from a collar 21 which by a screw key 22 is fixed to a sleeve 23, free on a stationary shaft 24. This shaft supports a plurality of these collars. They are all keyed to the sleeve 23 which extends along the shaft so that only one of the cams 18 has to be employed to operate a series of these devices which constitute a part of the slitting means.

On each collar 21 is fixed a segmental blade 25 which has a flat surface furnishing a cutting edge and is backed off along a surface 26 at each end in the form of a cam. This constitutes one element of a slitting couple. The segmental knife is backed off on each end to provide a slanting surface at each end so as to enable the cutter 35 to be forced back to cutting position gradually when the segment has been swung out for threading and is then brought back to position. The cutter 35 is pressed against this surface by a spring 37.

On a stationary shaft 30 is carried an integral track or guide 31 and a series of carriages 32 are adjustable along this track or pair of ways and fastened to the same in any desired position by screws 33. Each carriage 32 supports a motor 34 on the shaft of which is fixed a sharp circular slitter 35. Each of these slitters cooperates with one segment 25 to constitute a slitter couple.

The motors are carried in ways on the carriages 32 and adjusted by screws 36 by which the slitters can be moved toward and from the web of paper. Of course, they are located so as to project through it and slit it in the manner shown in Fig. 4.

It will be seen that the segments 25 are removable and replaceable and also that the cutters 35 are all driven separately but they are adjustable in any direction and that the knives are quickly and easily removed for sharpening.

It will be seen that the operation involves

the constant rotation of the slitting knives 35 on stationary axes at high speed and the oscillation of the segments 25 on a stationary axis.

5 When the paper is to be threaded through the machine the roller 19 has to be disconnected from the cam and the segments 25 turned down so that the upper edge is considerably below the slitters 35 so as to allow 10 the web to be threaded through as shown in Fig. 1. Then with the slitters 35 running the roller 19 is placed in the cam slot again and the machine started up.

Although I have illustrated and described 15 only a single form of the invention I am aware of the fact that modifications can be made therein by any person skilled in the art without departing from the scope of the invention as expressed in the claims. Therefore, I do not wish to be limited in this respect but what I claim is:—

1. In a slitting device for a paper winding machine, the combination with a series of circular slitting cutters and means for rotating 25 each one independently at high speed, of a sector shaped member located back of the web adjacent to each slitting knife and means for oscillating said sector shaped member on its own axis to constantly present new surfaces to the web at all times.

2. In a slitting device, the combination with a circular slitting cutter and means for rotating it at high speed, of a sector shaped member located back of the web adjacent 35 to the slitting cutter and means for oscillating said sector shaped member on its own axis.

3. In a slitting device, the combination of 40 a support, a carriage adjustable along the support, means for securing the carriage in any desired position on the support, a motor adjustable transversely on the carriage, a circular slitting knife directly on the shaft of said motor, a stationary shaft parallel with 45 the support, a sleeve on the stationary shaft free to turn thereon, a collar on the sleeve, means for securing the collar to the sleeve, a sector shaped blade adjustably secured to said collar and located at the side of the slitting knife to support the web, and means for 50 operating said collar constantly when the machine is in operation.

4. In a slitting device, the combination of 55 a support, a carriage carried by the support, a motor, a circular slitting knife directly on the shaft of said motor, a stationary shaft parallel with the support, a sleeve on the stationary shaft free to turn thereon, a collar on the sleeve, means for securing the 60 collar to the sleeve, said collar having a sector-shaped projection, a sector shaped blade secured to said projection and located at the side of the slitting knife, and means for oscillating said collar.

5. In a web slitting device, the combina-

tion with a cam and a cam roller therefor, of a stationary shaft, a collar oscillatable on the shaft and having an arm which supports said roll, a sector shaped blade carried by said collar and oscillatable by the cam on the axis 70 of said shaft and a circular slitting knife rotatable at high speed on the other side of the web and positioned to penetrate the web at the side of said sector shaped blade, said sector shaped blade being backed off at the ends 75 for the purpose described.

In testimony whereof I have hereunto affixed my signature.

FREDERICK W. LODDING.
